CLAIM

We claim the ornamental design for packaging for a pipe
wrench, as shown and described.

DESCRIPTION

FIG. 1 is a perspective view of a packaging for a pipe
wrench according to our new design;

FIG. 2 is a front side view of the packaging shown in FIG.
1.

FIG. 3 is a left side view of the packaging shown in FIG. 1.
FIG. 4 is a right side view of the packaging shown in FIG.
1.

FIG. 5 is a top side view of the packaging shown in FIG. 1;
and,

FIG. 6 is a bottom side view of the packaging shown in FIG.
1.

The present application is directed to the design illustrated
in the drawings. The elements shown in broken lines are
included for the purpose of illustrating environment and
form no part of the claimed design. The broken lines having
unequal line segments illustrate the boundary of the claimed
design.
